UNITED STATES PATENT OFFICE.

GEORGE LANE, OF POUGHKEEPSIE, NEW YORK.

DESIGN FOR A CYCLE-HANGER.

SPECIFICATION forming part of Design No. 26,033, dated September 15, 1896.

Application filed July 29, 1896. Serial No. 600,987. Term of patent 14 years.

To all whom it may concern:

Be it known that I, GEORGE LANE, a citizen of the United States, residing at Poughkeepsie, in the county of Dutchess and State of New York, have invented and produced a new and original Design for Cycle-Hangers; and I do declare the following to be a full, clear, and exact description of the same, reference being had to the accompanying drawings, forming a part thereof.

Figure 1 is a front elevation of a cycle-hanger, showing my design. Fig. 2 is a view in perspective looking downward and toward the right-hand side of the hanger.

15 The leading feature of my design consists of a plate curved to form parallel sides or cheeks for the hanger, and which are turned outward at their upper ends, and said plate at its front or curved portion cut away from below upward to about the middle of the plate. When viewed in front elevation, as in Fig. 1, the cut-away portion of the curved portion has the appearance of an inverted V.

25 11 are the sides or cheeks of the hanger, which are parallel throughout the greater portion of their length and which are united at the upper portion of their front ends by the curved portion 2. The sides or cheeks are also turned outward at their upper ends 30 33 laterally in the same horizontal plane.

The front portion 2 has the converging edges 44, which unite at 5 as a curve.

When viewed from the front, my design has the appearance of a parallelogram with diverging horizontal arms at the top and cut 35 away at the bottom, as a slot with converging sides.

In the portions 33 appear small circular openings 66 and in the side 1 a larger circular opening 7. The rear corners of the sides 40 1 are also curved, as at 8, and the corners of the plates 3 are also curved, as at 9.

Viewed from the side, as in Fig. 2, the design shows the body of my design substantially rectangular, with curved corners and 45 with diverging horizontal plates substantially at right angles to the sides of the hanger.

The result is a cycle-hanger which when viewed in any direction presents a smooth, well-balanced outline of plain surfaces and 50 curves without any angles or sharp corners.

What I claim is—

The design for cycle-hangers, substantially as herein shown and described.

In testimony whereof I affix my signature 55 in presence of two witnesses.

GEORGE LANE.
